RADIO RECEIVING CIRCUIT

Henry P. Kalmus, New York, N. Y., assignor to
 Emerson Radio & Phonograph Corporation,
 New York, N. Y., a corporation of New York

Application November 1, 1939, Serial No. 302,285

5 Claims. (Cl. 250—40)

This invention relates to improvements in radio receiving circuits and particularly those employed in super-heterodyne radio receiving sets.

5 An object of this invention is the provision of an improved super-heterodyne receiving circuit whereby it is adapted to receive frequency modulated signal waves.

An important object of this invention is the 10 provision of an improved form of circuit of the above type which has been simplified while improving the efficiency thereof.

A still further object of the invention involves the simplification of the so-called discriminating 15 and limiting portions of a super-heterodyne radio receiving circuit adapted to respond to frequency modulated carrier waves.

A more specific object of the invention is to provide in an arrangement of the above type a 20 single vacuum tube device and associated circuits for performing both the limiting and discriminating functions in frequency modulated receiving circuits.

These and other objects as will appear from 25 the following disclosure are successfully secured by means of the invention herein described.

This invention resides substantially in the combination, construction, arrangement and relative 30 location of parts, all as will be described in full detail below.

In the accompanying drawing:

Figure 1 is a diagrammatic illustration of that 35 portion of a super-heterodyne radio receiving circuit adapted to receive frequency modulated waves illustrating the subject matter of this invention; and

Figure 2 is a chart of the potential distribution 40 within the vacuum tube of this invention which is employed in accordance therewith to accomplish both the limiting and discriminating functions of such apparatus.

As is known in the art any radio receiving circuit adapted to reproduce the modulating current, which is of course the current representative 45 of the signal, of a frequency modulated carrier, commonly employs portions of the circuit for limiting the amplitude of the signal wave and for demodulating the limited wave to produce an audio frequency signal current which is 50 of course the original modulating current. In the prior art arrangements for accomplishing this purpose the output of the intermediate frequency amplifier of a super-heterodyne receiver is fed into a pentode vacuum tube, the output current 55 of which has been limited in amplitude. This

current so limited is then fed into a push-pull vacuum tube rectifying system through a frequency discriminating coupling system in such a way that the output thereof contains a direct current component which is substantially similar in all respects to the original modulating current, that is the original signal current. This portion of the apparatus which is known as a discriminator is fairly complex and represents a portion of the circuit distinct from the limiter portion referred to above.

In accordance with this invention substantial simplification of the discriminating portion of the circuit is accomplished. A simple resonant circuit and a suitable multi-grid vacuum tube takes 15 the place of the pentode previously used and the limiting and the discriminating functions are performed thereby with further attendant advantages hereinafter to be described.

At 1 is diagrammatically illustrated a portion 20 of the last vacuum tube of the intermediate frequency amplifier commonly employed in a super-heterodyne receiving set. The output of this tube is fed through a suitable radio frequency transformer 2 to the input circuit of the multi-grid tube generally indicated by the reference 25 numeral 7. It may be assumed for purposes of description that the intermediate frequency is 3 megacycles. It follows therefore that the input circuit will be tuned to a frequency of 3 megacycles. The input circuit of the multi-grid tube includes the secondary of the transformer 2 shunted by a suitable capacitor 3 with the values thereof fixed to render the combination resonant at 3 megacycles. One terminal of this combination of inductor and capacitor is connected 30 by wire 4 through a capacitor 5 to the control grid 6 of the multi-grid tube 7. The other terminal of the resonant circuit is connected by the wire 8 to the cathode return lead 9. The 35 cathode 13 of the tube 7 is connected by a wire 10 through a suitable resistor 11 to the cathode return 9. The resistor 11 is shunted by a capacitor 12 of suitable value to by-pass the radio frequencies present. A suitable grid leak resistor 40 45 34 is connected between the cathode 13 and the control grid 6.

As diagrammatically illustrated the multi-grid tube 7 may include a grid 14, adapted to be connected by a wire 15 to the positive side of a 50 suitable potential source so as to maintain this grid positive with respect to the cathode in accordance with usual practice. A suitable high frequency by-pass circuit is provided between the lead 15 and the cathode return 9 by means 55

of a properly proportioned capacitor 16. The 5 multi-grid tube 7 has a third grid 17, a fourth grid 18, and a fifth grid 19. The grids 17 and 19 are provided with a common lead 20 which is connected to the positive terminal of a suitable potential source and a by-pass capacitor 21 is provided between the lead 20 and the cathode return 9. The grid 18 is connected to the return lead 9 by a lead 22 through a resonant circuit 10 comprising the inductor 23 and the capacitor 24. This circuit is tuned to resonance at 3 megacycles. It may be noted, as indicated diagrammatically, that the grids 6, 14, 17, 18 and 19 are 15 spatially distributed within the envelope of the multi-grid tube in the manner illustrated. The distribution of the elements and the pitch of the grids determines the limiting action of the tube.

The plate or anode 25 of the tube 7 connected by a wire 26 through a suitable resistor 27 of the 20 order of 50,000 ohms to the positive side of the plate current source and lead 26 is connected through a suitable by-pass capacitor 28 to the cathode return lead 9. Wire 26 is connected by a wire through a capacitor 29, a high resistor 30, and a resistor 31 of lower value to the return lead 9. The common point of resistors 30 and 31 is connected through a capacitor 32 to the return lead 9. A suitable adjustable connection 33 together with the return lead 9 provide the 30 output terminals for this apparatus which would be coupled in any suitable manner to an audio signal responsive device such as a loud speaker or an audio frequency amplifier if amplification is desired.

35 Figure 2 illustrates diagrammatically the potential distribution in the multi-grid tube 7 between the cathode and plate along a theoretical line which does not cut any of the turns of the grids. When grid 18 is negative the electrons 40 passing through grids 6 and 17 are partially impeded with the result that a virtual cathode is formed before the grid 18. During the time grid 6 is positively charged this virtual cathode causes a bending in the curve of potential between grids 45 17 and 18 as indicated in Figure 2. During the time grid 6 is negatively charged, that is when it is sufficiently negative, there is practically no space charge before grid 18, with the result that the potential distribution between grids 17 and 50 18 is practically a straight line, as indicated by the dotted line in Figure 2 in the space represented as corresponding to the space between grids 17 and 18. The dotted line in the space between the cathode and grids 6 and 14 indicates 55 a negative potential distribution when the grid 6 is sufficiently negative. The solid line C represents the potential distribution from cathode to plate when grid 6 is positive and for different positive values thereof, with the variation indicated in the dotted line in the region between grids 17 and 18 during the negatively charged time of grid 6. This chart serves to further demonstrate that the space charge periodically formed before grid 18 periodically charges that grid. 60

65 If it is imagined that grid 18 is connected to the cathode through a condenser this induced charge causes a periodic charging of the condenser and a simultaneous alternating current voltage between grid 18 and the cathode. This voltage is 70 changing at the same rate as the space charge and the alternating current voltage on grid 6. When this is at maximum positive value most of the electrons are crowded before grid 18, and this grid becomes negative if there is a capacity reactance between grid 18 and cathode. There-

fore, the alternating current voltage introduced between grid 18 and the cathode is just out of phase with the alternating current voltage between grid 6 and the cathode. As stated another way, it can be imagined that there is an 5 apparent negative capacity between grids 6 and 18. There is no such apparent negative capacity in the opposite direction between grids 18 and 6. Therefore, the described effect is comparable with a negative capacity in one direction. By reason of these characteristics it is possible by connecting a resonant circuit properly tuned between the grid 18 and ground to perform the discriminating functions desired in apparatus of this type when adapted to the reception of frequency modulated signal waves. 15

In order to understand the operation of this circuit the action which goes on in the multi-grid tube needs some description. Before giving this description it will be noted, however, as 20 is apparent to those skilled in the art, that all of the circuit connections for the portion of the circuit shown have not been completed because their completion is apparent to those skilled in the art, and by omitting certain portions the disclosure is thereby simplified. As noted above, the grid 6 is the control or input grid of the tube, which grid is initially grid leak biased so as to be negative with respect to the cathode. The grids 14, 17 and 19 are maintained positive 30 with respect to the cathodes, whereas the grid 18 is made negative with respect to the cathode by resistor 11. A space charge is present between grids 17 and 18 depending on grid 6 potential. This space charge is varying in accordance with the alternating current voltage on grid 6. This variation of the space charge produces an alternating current voltage on grid 18 by capacitive induction. If there is a capacity reactance between grid 18 and cathode 40 return lead 9 this capacity is charged and discharged in the same phase as the space charge varies at grid 18. In other words, the alternating current voltage produced on grid 18 of the same frequency as that present on grid 6 is 180 45 degrees out of phase with grid 6 voltage, thereby decreasing the slope of the characteristic of the plate current, as well as the plate current of the tube. If an inductive reactance is present between grid 18 and cathode return lead 9 the 50 voltages on grids 6 and 18 will be in phase, thereby increasing the slope of the characteristic of the plate current and therefore the plate current of the tube. On the other hand, if resistance is present between grid 18 and lead 9 the voltages 55 of grids 6 and 18 are ninety degrees out of phase so that no change occurs in the slope of the plate current characteristic. Therefore, if a resonant circuit including an inductor and a capacitor is inserted between the grid 18 and return lead 9, 60 depending upon the relationship of the resonance frequency thereof and the frequency applied to grid 6, the useful results of this invention may be secured.

With such an arrangement the plate current 65 changes progressively with the frequency of the voltage variation of grid 6, i. e., the plate current changes proportionately and in the same direction as the input frequency. Hence, if, with the frequency characteristics of the resonant 70 circuit 23-24 fixed, the control grid frequency changes, the plate current changes in the same way. The result is that the output of the circuit, as illustrated in Figure 1, is the same as the output of the conventional discriminator 75

previously mentioned. The slope of the plate current characteristic, however, when plotted against the input frequency is much greater by this arrangement, with the result that this device is more sensitive and has greater output.

The arrangement also can act as a limiter, cutting off, so to speak, the tops of the frequency modulated carrier, as well as all portions of extraneous noises such as static above the amplitude of cut-off providing the desirable limiting function of a circuit of this type. Limiting is accomplished by grid circuit cut-off due to condenser 5 and grid leak 34 and by plate circuit cut-off due to proper choice of voltage on and 15 geometry of grids 14 and 17, as is well known in the art.

From the above description it will be apparent to those skilled in the art that I have devised certain new and novel circuit combinations 20 which produce advantages of practical importance and that the embodiment of the invention herein disclosed for the purpose of illustrating the invention is capable of variation without departure from the novel scope of the 25 subject matter herein disclosed. I do not, therefore, desire to be limited by this disclosure but rather by the scope of the claims granted me.

What is claimed is:

1. In a combined radio frequency carrier operated limiting and discriminating circuit, the combination including a multi-electrode vacuum tube including a cathode, an anode and a plurality of control electrodes, a tuned input circuit including one of said control electrodes and said 35 cathode, an output circuit including said anode and said cathode, means for biasing the control electrode independently of the other electrodes, means for biasing others of said control electrodes, the biasing of said biased electrodes being 40 selected to limit the response to the amplitude of the input, and a resonant impedance network connecting another of said control electrodes with said cathode whereby the current in said output circuit is varied by and in accordance with 45 changes in the frequency on the first control electrode.

2. In a radio circuit combination, a vacuum tube having a cathode, an anode and a plurality of grids, an input circuit connected to one 50 of said grids and said cathode, an output circuit

connected to said anode and said cathode, means connected between said cathode and another of said grids for causing the current in the output circuit to change progressively with changes in frequency in the input circuit, and means for biasing one or more of the grids to limit the response to the amplitude of the input. 5

3. In a combined radio frequency carrier operated limiting and discriminating circuit, the combination including a multi-electrode vacuum 10 tube including a cathode, an anode and a plurality of control electrodes, a tuned input circuit including one of said control electrodes and said cathode, an output circuit including said anode and said cathode, means for biasing the control 15 electrode independently of the other electrodes, means for biasing others of said control electrodes, the biasing of said biased electrodes being selected to limit the response to the amplitude of the input, and a resonant impedance network 20 having a resistance component connecting another of said control electrodes with said cathode whereby the current in said output circuit is varied by and in accordance with changes in the 25 frequency on the first control electrode. 25

4. In a radio circuit combination, a vacuum tube having a cathode, an anode and a plurality of grids, an input circuit connected to one of said grids and said cathode, an output circuit connected to said anode and said cathode, means 30 connected between said cathode and another of said grids for causing the anode current to change progressively with changes in the frequency on the first grid, and means for self biasing the input grid to limit the response to the 35 amplitude of the input.

5. In a radio circuit combination, a vacuum tube having a cathode, an anode and a plurality of grids, an input circuit connected to one of said grids and said cathode, an output circuit 40 connected to said anode and said cathode, a resonant impedance network connected between said cathode and another of said grids for causing the current in the output circuit to change progressively with changes in the frequency in the 45 input circuit, and means for biasing the input grid, this biasing being selected in relation to the shape and spacing of said grids to limit the response to the amplitude of the input.

HENRY P. KALMUS. 50
